UNITED STATES PATENT OFFICE.

MINOT S. PARTRICK, OF SOUTH NORWALK, CONNECTICUT, ASSIGNOR OF ONE-HALF TO WILLIAM HOBSON, OF SOUTH NORWALK, CONNECTICUT, AND ONE-FOURTH TO PATRICK F. CROTTY AND ONE-FOURTH TO JOHN MYLOD, OF NORWALK, CONNECTICUT.

KNOB ATTACHMENT.

No. 831,981.

Specification of Letters Patent.

Patented Sept. 25, 1906.

Application filed July 16, 1903. Serial No. 165,770.

To all whom it may concern:

Be it known that I, MINOT S. PARTRICK, a resident of South Norwalk, in the county of Fairfield and State of Connecticut, have invented certain new and useful Improvements in Knob Attachments, of which the following is a specification.

My invention relates to knob attachments, and has for its object to provide a complete knob which shall be easily and readily adjustable to all doors and which shall be cheap and economical of construction.

In the drawing forming part of this specification the figure is a view, partly in section, showing my invention.

A represents the knobs, which may be of any material or construction, having attached thereto the knob-shanks B, provided with sockets for the reception of the spindle 20 B'. The socket in the shank of each of the knobs is made square, and one face of the socket is provided with serrations or corrugations C. The spindle is formed with corresponding corrugations D. One of the 25 knob-shanks, the one to the left shown in the drawing, has a screw-threaded orifice, in which works the set-screw F. This set-screw is of a sufficient length to cause the corrugations on the spindle to engage with 30 those in the socket. It will be seen, therefore, that this spindle can be adjusted within the limits of its length within the socket.

The socket in the other knob-shank, the one shown to the right, is sufficiently larger 35 than the shank to allow the introduction of a key E'. This key is of such a thickness that when put in place it causes the serrations on the shank at that end to engage the serrations in the socket. A portion of the shank is 40 cut away, as shown at G, to allow the upturned end of the key to fit therein when pushed home. This key is not wedge-shaped, but of a thickness to allow its insertion and removal without the exertion of any great 45 force; but, as will be seen, when in place it

causes the two sets of serrations to engage, thus holding that particular knob in any position in which it may be adjusted.

From the above description it will be seen that a knob attachment is produced which is 50 readily adjustable to any thickness of door and of such a form that the adjustment is capable of variations within very small limits. It does away with the necessity for washers, allows an exceedingly close adjustment, is 55 very simple in its construction, and almost avoids the necessity for machine-work, for the serrations on the shank may be stamped, the serrations in the knob-shanks may be cast, and all adjustments are quickly and 60 easily made.

What I claim, and desire to secure by Letters Patent, is—

1. A knob attachment consisting of a knob, a shank, said shank having a socket, 65 said socket being provided with serrations on one of the inner walls thereof, a spindle having flat sides, one of said flat sides being provided with complementary serrations, and means fitting between one of the walls of the 70 socket of the shank and one of the flat sides of the spindle to hold the serrations in engagement with each other.

2. A knob attachment consisting of a knob, a shank, said shank having a socket, 75 said socket being provided with serrations on one of the inner walls thereof, a spindle having flat sides, one of said flat sides being provided with complementary serrations, and a key between the shank and one of the flat 80 sides of the spindle to hold the serrations in engagement.

In witness whereof I have hereunto set my hand, at South Norwalk, in the county of Fairfield and State of Connecticut, this 11th 85 day of June, 1903.

MINOT S. PARTRICK.

In presence of—

FRANK E. MATHER,
GUSTAV PITZER.
